UNITED STATES PATENT OFFICE.

RAY E. DUNHAM, OF BEREAL, OHIO, ASSIGNOR TO THE DUNHAM COMPANY, OF BEREAL,
OHIO, A CORPORATION OF OHIO.

LAND-ROLLER.

1,198,015.

Specification of Letters Patent. Patented Sept. 12, 1916.

Application filed August 20, 1915. Serial No. 46,534.

To all whom it may concern:

Be it known that I, RAY E. DUNHAM, a citizen of the United States, resident of Berea, county of Cuyahoga, and State of Ohio, have invented a new and useful Improvement in Land-Rollers, of which the following is a specification, the principle of the invention being herein explained and the best mode in which I have contemplated applying that principle, so as to distinguish it from other inventions.

My invention relates to land rollers and particularly to rollers in which water or sand is used as a ballast.

15 The object of the invention is to provide a roller construction in which the drum may be manufactured economically and in a water-tight manner, and in which at the same time, certain parts of the drum are so arranged as to protect the joint formed between the shell and end heads, strengthen the ends of the drum and avoid marking or marring the lawn or other surface upon which it may be used.

20 25 The said invention consists of means hereinafter fully described and particularly set forth in the claims.

In the annexed drawing: Figure 1 represents an axial section of a roller drum embodying my invention. Fig. 2 represents an axial section of a fragmentary portion of said drum, upon an enlarged scale.

The illustrated embodiment of my invention comprises an outer metal sheet bent to form a cylindrical shell 1 and having its meeting ends butt-welded in the usual manner. In each end of the shell respectively, is a head 2 formed with a central opening 3 and in these openings are secured in a water-tight manner, the ends, respectively, of a hollow central tube 4, preferably by welding. Each head is formed with an outwardly extending flange 5, these flanges fitting snugly within the interior of the shell, as shown. The end portions of the shell or cylinder, as well as the end portions of the flanges, are bent to form an inwardly extending rib 6, as clearly shown in Fig. 2, and the extremities of these end portions are integrally united by welding, thereby forming a water-tight joint. The bending is effected in a manner such as to produce a smooth rounded end surface as at 7, as a result of which these ends avoid marking or marring of the surface upon which the

roller is used, to a very large degree. The curve at 7 being an easy one, the contacting surface of the flange and drum are not disturbed in their close relations, and there is little slipping during bending, the outer sheet being merely stretched a little during the bending, this stretching occurring apparently on a circumference drawn from the center of curvature. In other words, a radius line drawn from said center through 60 the two sheets, before the curving, would not be found much distorted after bending. This is important, as it enables me to maintain a tight joint, easily. The less this metal is bent or strained, the more easily is this 65 effected. I aim, therefore, to turn the rib 6 inward far enough to insure the curve desired and constitute the reinforce referred to below. The seam, therefore, is between parts bent upward to any angle less than a 70 reentrant angle, i. e., an angle reentrant with respect to the outer wall of the drum and the axis of rotation. The inner edges of the joint are preferably (though not necessarily) 75 made flush with each other. The joint thus lies in the surface of a circle (or cone), the center of which circle or cone lies in the axis of rotation of the cylinder. Furthermore by bending these end portions of the shell and flanges inwardly to form the described rib 6, it will be seen that this rib is so placed that it provides a very efficient 80 reinforcement for the extreme ends of the drum which renders these ends very stiff and hence permits them to resist deformation when meeting obstructions in the course 85 of its use. Furthermore the weld being located as described, it will be seen that it is placed at the most advantageous point for its protection, being not only removed as far as possible from the surface upon which the roller is used, but also being placed adjacent to the inner surface of the strengthening rib. The possibility of the weld being opened when the roller meets an obstruction is therefore reduced to a minimum, as will be readily understood.

Having fully described my invention, what I claim and desire to secure by Letters Patent is:—

1. In a land-roller, the combination with a sheet of metal bent to form a cylindrical shell; of two end heads each consisting of a main or body-portion and a peripheral flange; said flanges being in contact with 110

the inner surfaces respectively of the end-portions of the cylinder; the end-portions of said sheet and flanges being bent inwardly toward the axis of the cylinder the joints 5 between the inturned flanges and cylinder ends lying in surfaces situated at angles less than a reentrant angle to the axis of rotation and integrally united to each other at their extremities.

- 10 2. In a land-roller, the combination with a sheet of metal bent to form a cylindrical shell; of two end heads secured to said shell, each formed with an outwardly extending flange; the end portion of said flanges and 15 corresponding end-portions of said shell being bent around toward the shell's axis to form a strengthening rib, the joint formed between the ends and flanges lying in surfaces situated at angles less than a reentrant 20 angle to the axis of rotation.

3. In a land roller, a drum consisting of a cylindrical shell, two end-heads secured therein, the ends of said shell being bent inwardly toward the axis of the drum at 25 an angle less than a reentrant angle, the joint extending toward the axis of rotation; said end-heads being formed with flanges and inset in the ends of said shell, said flanges being integrally united with the 30 latter.

4. In a land roller, the combination of a sheet of metal bent to form a cylindrical shell of uniform exterior contour; two end heads each consisting of a main or body 35 portion and a peripheral flange; said flanges being in contact with the inner surfaces respectively of the end portions of the cylinder; the end portions of said sheet and flanges being bent inwardly toward the axis 40 of the cylinder at an angle less than a reentrant angle, the joint at its ends extending toward the axis of rotation and integrally united to each other at their extremities; and axial means connecting said two heads.

45 5. In a land roller, a drum consisting of a cylindrical shell of uniform exterior con-

tour, two end heads secured therein, the ends of said shell being curved inwardly toward the axis of the drum; said end heads being formed with flanges and inset in the ends of 50 said shell, said flanges being also curved inwardly toward the axis of the drum in close contact with the inturned ends, the joint at its inner edges extending toward the axis of rotation at an angle less than a reentrant 55 angle and being integrally united with the latter.

6. In a land roller, a drum, a head for said drum, said head having a longitudinally and outwardly extending flange, said 60 drum and flange being turned inward toward the axis, the contact between them being preserved in a surface inclined at an angle less than a reentrant angle to the axis of rotation.

7. In a land roller, a drum, a head for said drum, said head having a longitudinally and outwardly extending flange, said drum and flange being turned inward toward the axis, the contact between them being preserved in a surface inclined at an 70 angle less than a reentrant angle to the axis of rotation, the drum and flange being secured together at their contacting inner edge and said inturned edge forming a reinforcing 75 for the roller.

8. In a land roller, a drum, a head for said drum, said head having an outwardly extending flange, the end of said drum and said flange being in water-tight contact 80 turned or bent inward toward the drum axis on a curve of sufficient radius to permit the maintenance of said water-tight connection, and said drum and flange constituting a strengthening web for the roller.

Signed by me, this 16th day of August, 1915.

RAY E. DUNHAM.
